UNITED STATES PATENT OFFICE.

WASHINGTON H. KILBOURN, OF GREENFIELD, MASSACHUSETTS.

TROLLEY-POLE-CONTROLLING DEVICE FOR CARS OR VEHICLES.

SPECIFICATION forming part of Letters Patent No. 691,275, dated January 14, 1902.

Application filed April 10, 1901. Serial No. 55,164. (No model.)

To all whom it may concern:

Be it known that I, WASHINGTON H. KILBOURN, a citizen of the United States, residing at Greenfield, in the county of Franklin 5 and State of Massachusetts, have invented new and useful Improvements in Trolley-Pole-Controlling Devices for Cars or Vehicles, of which the following is a specification.

This invention relates to improved means 10 for governing the movement or upward throw of the trolley-pole of an electrically-propelled trolley-car when the free end of said pole becomes disengaged from under the conducting-wire and unless restrained flies upward 15 above said wire, thereby cutting off the current from the car and oftentimes damaging the line by striking and breaking guy-wires and disarranging other fixtures thereof, the object being to provide an improved trolley-pole controller intermediate of the free end 20 of the trolley-pole and car, whereby the normal vertical movements of said free end consequent upon variations in the height of the conducting-wire under which it bears are 25 regulated to such a degree as to insure practically a continual contact with said conductor, but in case the free end of said pole from any cause becomes displaced from under the said conductor it is automatically prevented 30 from swinging but slightly, if at all, above the latter, thereby preventing said damaging results, and the pole can be conveniently replaced under the conducting-wire by the attendant on the car without materially interrupting the movement of the latter.

In the drawings forming part of this specification, Figure 1 is a side elevation of a part of the roof and of one end of a trolley-car, illustrating the position of a section of the 40 conducting-wire thereabove, the usual trolley-pole and its supporting and spring-actuating devices on said rod and trolley-pole-controlling devices embodying my invention, attached to said car part, and a connection 45 between said controller and pole. Fig. 2 is a perspective view of a part of the end of the car shown in Fig. 1, but upon an enlarged scale, in which said controller is shown with a portion of one border partly broken away. 50 Fig. 3 is a perspective view of one end of the controller-frame, illustrating a modified con-

struction of a part thereof, hereinafter described.

Referring to the drawings, A indicates one end of a trolley-car; B, the usual dashboard 55 or fender on the border of the platform, and I the platform.

D indicates the trolley-pole, E the pivotal and spring-actuated support of said pole on the roof of the car, and F the trolley-pole cord 60 connecting the same with said controller. Said pole-controller is indicated by J, and structurally comprises an oblong frame, of metal or wood, as may be preferred, of rectangular form in cross-section, having two 65 end pieces or heads united by four parallel separated bars 3 between said heads, as clearly shown in Fig. 2. Between said bars are four longitudinal slots or openings, as shown, which provide runways for a trolley- 70 pole counterweight 5 and for the shaft 6, forming the trunnions thereof, as shown. Said counterweight has the form of a grooved pulley and is preferably of metal. As shown in Fig. 2, the ends of said shaft 6 extend outwardly between the upper and lower bars of 75 said frame, while the counterweight-pulley is adapted to move centrally between said four bars back and forth between the ends of said frame. The under sides of the upper bars of 80 said oblong frame are provided with either a series of depending pins 4, as in Fig. 2, or said bars are serrated, as shown at x in Fig. 3, and in either case the space between the points of said pins 4 or the teeth of said serrations 85 of the bars and the adjoining upper side of the bar 3 thereunder is wide enough to permit said shaft 6 to move or roll freely on said under bar back and forth between the ends of the pole-controller frame, and the spaces 90 either between said pins 4 or between the teeth of said serrations are wide enough to receive the parts of said shaft 6 which extend beyond the sides of said counterweight 5 when the latter shall be lifted up and off from 95 the under bars of said frame, as below described. Said frame is suitably secured on the dashboard B of the car in such degree of inclination as will cause said counterweight 5 to roll freely downward under certain circumstances, as below set forth, whereby the 100 trolley-pole cord F is kept taut with a certain

force, but not sufficient to interfere with the proper electrical contact thereof with the conducting-wire C, to the end that there shall be normally no "slack" in said cord, which would 5 permit said pole to spring above said conductor while the car is moving.

The operation of the within-described trolley-pole-controlling devices is as follows: The lower end of the trolley-pole cord F is passed 10 around said pulley-shaped counterweight 5, and the end thereof is secured to the upper end of the frame of the controller J, as shown in Figs. 2 and 3, by knotting the same or otherwise. In practice the position of said counterweight 5, with the trolley-pole D in the position shown in Fig. 1, relative to the conducting-wire C would be rather nearer the lower end of the controller-frame than is shown in said figure. A hook-coupling H 15 may, if desired, be placed in the pole-cord F for convenience in passing the same around said counterweight. Figs. 1 and 2 fairly illustrate the positions of the trolley-pole D, the pole-cord F, and the counterweight 5, which 20 they relatively occupy while the car is moving on a road. While the car so moves said weight moves upward and downward on said controller-frame in consonance with the similar swinging movements of the upper end of 25 the trolley-pole as it follows the common undulations of the conducting-wire C, but keeping said cord constantly in line. When, however, the upper end of said pole suddenly leaves the conductor and by the pole-spring 30 support E is carried upward more or less, the force of said movement through the cord F acts suddenly upon the weight 5 and instantly 35 lifts it bodily upward, carrying the ends of the shaft 6 off from the lower bars of the con-

troller-frame and up into such sudden engagement against the sides of the pins 4 thereabove that the weight has no rotary movement in this action, but serves to instantly stop the movement of said pole upwardly, thereby preventing the end of the pole from 40 swinging above said conductor, with the damaging results above mentioned, and holding the pole-cord in such position that an attendant on the car-platform can easily swing the end of the pole into proper position under 45 said conductor-wire.

Having thus described my invention, what I claim, and desire to secure by Letters Patent of the United States, is—

1. Trolley-pole-controlling devices comprising the trolley-cord, a weight with which the cord has a rolling engagement, an inclined track over which said weight moves, actuated by the normal vertical movement of said cord, combined with means whereby a sudden lifting movement applied to said weight will arrest the latter, substantially as described. 55

2. Trolley-pole-controlling devices comprising two parallel inclined tracks, a weight having trunnions thereon for supporting it on the tracks between the latter, a trolley-cord passing around a part of the weight concentric with said trunnions and having its free end attached to the car above said weight, combined with a toothed rack parallel with the 60 tracks and located above them, adapted to be engaged by said trunnions when the weight is suddenly lifted, substantially as described. 65
